UNITED STATES PATENT OFFICE.

GUSTAV BRUECK, OF NEW YORK, N. Y.

DESIGN FOR A CARD-COVER.

SPECIFICATION forming part of Design No. 13,040, dated July 18, 1882.

Application filed June 8, 1882. Term of patent 3½ years.

To all whom it may concern:

Be it known that I, GUSTAV BRUECK, a citizen of the United States, residing at New York, in the county and State of New York, have invented and produced a new and original Design for Covers for Cards and other Articles, of which the following is a specification, reference being had to the accompanying drawing, forming part thereof.

10 This design consists in a fringed border on the edges of both flaps of the cover, and in a turned-over corner on one flap, said corner being also provided with a fringed edge, so as to impart to the article a novel and ornamental 15 appearance. The corner of the flap which is opposite to the turned-over corner is ornamented with arabesques.

The drawing represents a perspective view of my cover.

20 In this drawing, the letters A B designate the two flaps of my cover, which are connected so that they can be folded or unfolded. The edges of both these flaps are ornamented by fringed borders *a*, and the flap A is provided

with a turned-over corner, C, the edges of which are ornamented by fringed borders *b*. The corner D of the flap A, which is opposite to the turned-over corner C, is ornamented on its surface by arabesques *c*, as shown.

What I claim as new, and desire to secure by Letters Patent, is—

1. The design for a card-cover, consisting of fringed borders *a* on the edges of the flaps A B, and of a turned-over corner, C, having fringed borders *b*, as shown and described. 35

2. The design for a card-cover, consisting of fringed borders *a* on the edges of the flaps A B, a turned-over corner, C, having fringed borders *b* and arabesques *c* on the corner D opposite to the turned-over corner C, as shown 40 and described.

In testimony whereof I have hereunto set my hand in the presence of two subscribing witnesses.

GUSTAV BRUECK.
